UNITED STATES PATENT OFFICE.

HENRY F. ODENKIRCHEN, OF NEW HAVEN, CONNECTICUT, ASSIGNOR OF
ONE-THIRD TO WILLIAM G. COWELL, OF NEW HAVEN, CONNECTICUT.

BOX-MACHINE.

No. 829,995.

Specification of Letters Patent.

Patented Sept. 4, 1906.

Application filed May 15, 1905. Serial No. 260,434.

To all whom it may concern:

Be it known that I, HENRY F. ODENKIRCHEN, a citizen of the United States, residing at New Haven, in the county of New Haven and State of Connecticut, have invented certain new and useful Improvements in Box-Machines, of which the following is a specification, reference being had therein to the accompanying drawings.

10 My invention relates to new and useful improvements in box-machines, and refers more particularly to that type of box-machine by which the neck or collar is inserted and secured within the body of a box.

15 It is the object of my invention, among other things, to provide mechanism whereby the paper strip surrounding the box-body may be turned inwardly and downwardly and the neck or collar placed within said box-

20 body, all of said operations being automatic, a further object being to construct a device to accomplish the results herein suggested with mechanism of few parts of such simple design as to be economically constructed and

25 readily assembled.

To these and other ends my invention consists in the box-machine having certain details of construction and combination of parts, as will be hereinafter described, and

30 more particularly pointed out in the claims.

Referring to the drawings, in which like numerals of reference designate like parts in the several figures, Figure 1 is a front elevation of my improved machine complete.

35 Fig. 2 is an enlarged sectional elevation of the plunger, taken upon line A B of Fig. 3. Fig. 3 is a sectional elevation of the machine, taken upon line A B of Fig. 5. Fig. 4 is an elevation of a portion of the cam mechanism

40 with adjacent parts. Fig. 5 is a plan view of the bed of the machine, the sectional parts being taken upon line A B of Fig. 1. Fig. 6 is a sectional elevation taken upon line C D of Fig. 5. Fig. 7 is a perspective view of a

45 box-body, showing the paper strip attached thereto and in condition to be placed in my machine. Fig. 8 is a perspective view of a box-body, showing the paper strip folded inwardly. Fig. 9 is a perspective view of the collar, and Fig. 10 is a perspective view of the completed box-body.

In the practice of my invention the box as

placed in the machine has a portion of the paper strip thereon projecting above the top of the box. This strip may be glued upon 55 its outside near the top thereof or the collar may be glued upon the outside, either mode of gluing being permissible. As the gluing means is not a part of this invention, it is neither shown nor described herein. The upwardly-projecting portion of the paper strip is now turned inwardly, after which the collar is inserted in the box, completing the same.

Referring to the drawings, the numeral 1 designates the bed of the machine, having the 65 openings 11, 12, and 13 through the top thereof and which is supported upon standards 2 2. Mounted within the journal-boxes 3 3 is the shaft 4, which is rotated by a pulley 5, driven by a belt, as is common in the art. 70 The pulley 5 is rotatable about the shaft 4 and preferably connected with said shaft by clutch mechanism of any preferred type, and for purpose of illustration I have represented a clutch-lever 6, that is connected by a rod 7 75 to a lever-arm 8, fixed on the shaft 9, which is mounted in the standards 2 2 and to which is affixed the foot-treadle 10. Lying upon the top of the bed between the ways 14 are the dies 15, 16, 17, and 18, which are held therein 80 by the caps 19. In the machine shown in the drawings the dies 15 and 16 are stationary and the dies 17 and 18 are movable. This construction I prefer for this particular type of machine, but desire it to be understood, 85 however, that all of the dies may be mounted so as to be movable, if desired. For economy of construction and to provide a wearing-surface each of said dies is provided with a face-plate 20. Resting upon the top of each of 90 said dies are the folders 21, which are provided with the beveled plates 22 at their inner faces and have the longitudinal slots 23 therein, through which project the pins 24, that are secured in the dies and located so as 95 to limit the movement of said folders in one direction. In the back edge of each of said folders are recesses 25, within which is inserted a coil-spring that abuts at one end against a shoulder upon the dies, the normal 100 action of said spring tending to press the folders inwardly.

The mechanism for actuating the die 17 comprises a barrel-cam 26, fixed on the shaft

4, an arm 27, having a roll upon one end thereof which enters the groove in the cam 26 and secured to a rock-shaft 28, which is mounted within a fixed block 29, and an arm 30, having 5 the screw 31 with the check-nut 32 thereon, the forward end of said screw bearing against the outer edge of the die. The rotation of the cam 26 actuates the roll-arm 27, rock-shaft 28, and arm 30 and moves the die 17 inwardly, 10 which die is returned to its original position by the spring 33, that is fixed to one of the posts 24 and to a post 34, fixed on the bed of the machine. In this construction, which is economical and sufficiently positive for all 15 practical purposes, the movement of the die is positive in only one direction; but it may be designed, however, so as to be moved positively in both directions.

The mechanism for actuating the die 18 is 20 very similar to that above described, there being a rock-shaft 35 rotatable in the fixed block 36 and having an arm 37 secured thereto and within which is threaded the bolt 38, which impinges against the outer face of the die 18, a roll-arm 39 fixed to the shaft 35 and 25 having a roll 40 thereon which lies against the periphery of the cam 41, the spring 42 being connected with the post 24 and the post 43 to draw the die to its outer position after it has 30 been moved forwardly by the mechanism above described.

Operative beneath the opening in the bed between the inner faces of the dies is a reciprocating slide 44, which moves between the 35 ways 45 integral with the bed and the caps 46 secured thereto. A reciprocating movement is given this slide through a rock-shaft 47, which is mounted within brackets 48, depending from the bed, a rock-arm 49, fixed 40 to said shaft and carrying a roll 50 upon its outer end which lies against the face of the cam 51 upon the shaft 4, an arm 52, fixed to said shaft, and a link 53, pivotally secured at one end to the arm 52 and at the other end by 45 the pintle 55 between the ears 54 upon the slide 44. The roll 50 is held against the periphery of the cam 51 by the spring 56, which is connected at one end to a fixed part upon the bed and the other end to a spring-arm 57, secured 50 to the shaft 47. Secured to the top of the slide 44 with its upper surface flush with the under side of the dies and movable within the opening 11 through the bed is the base-block 58, which is preferably secured to the 55 slide by screws 59. Fixed on the top of the bed is the head 60, within which is movably mounted the slide 61, that is reciprocated vertically from a cam 62, fixed upon the shaft 4, through a slide 63, that is operative within the box 64, and a rock-lever 65, pivotally mounted 60 midway between its ends upon the shaft 66 and one end of which enters a recess 67 in the slide 61 and the other end of which is connected with the slide 63 by the link 68.

The plunger mechanism comprises a body 65 member 69, a shank 70, which is fixed within the bottom end of the slide 61 by the cap 71, an adjusting-screw 72, having a check-nut 73 thereon threaded into the end of the said shank, the head of which is against the shoulder 74 on said slide, two spring-boxes 75, secured to the body member 69, a spring-plate 76, having spring-rods 77 attached thereto, which are surrounded by the coil-springs 78, that are within the spring-boxes 75, the jaws 79, which are movably mounted in said head member and secured therein by the caps 80, and a wedge 81, that is fixed in the lower end of the shank 70 and bears against the inner opposing faces of the jaws 79. These jaws 80 are normally held against the wedge 81 by springs 82, which lie between the said jaws and caps 83, fixed to the said body member.

In the drawings I have only illustrated two jaws; but I desire it to be understood 85 that my invention is equally applicable with three, four, or any other number of jaws.

In Figs. 7, 8, and 10 the box-body is designated as 84, the paper strip thereon as 85, and in Figs. 9 and 10 the collar as 86. 90

When the machine is at rest, the two movable dies are in their outer positions, the plunger is up, and beneath the opening under the dies the reciprocating slide is in the position shown in Fig. 5.

In operation the box-body 84, having the paper strip 85 thereon projecting upwardly above the top of the box-body, as shown in Fig. 7, is placed on the block 58 between the inner faces of the dies. A collar 86 is then 100 placed around the jaws 79, so that its top edge abuts against the shoulder 87, after which the mechanism is operated by depressing the treadle 10 and the dies 17 and 18 move inwardly toward the dies 15 and 16, respectively, centering the box, so that it is in register with the plunger and holding it securely between the same, the dies having been previously adjusted in relation to each other, so that the inward limit of their movement will hold the box without crushing it. The movable dies are adjusted by the screws threaded in the crank-arms 30 and 37 and the stationary dies by the screws 88, which are threaded into blocks 89 and arranged so that 115 their inner ends will impinge against the outer edges of the dies. During the movement of the dies the folders 21, which overhang the dies, turn the paper strip 85 inwardly, as shown in Fig. 8. The plunger 120 now moves downwardly, and as the bottom of the collar thereon engages the angular faces of the folders the same are moved outwardly and away from the plunger against the action of the springs 90 and the inwardly-projecting overhanging portion of the paper strip 85 is turned downwardly inside of the box by the collar as it is inserted within the 125

box. When the collar rests upon the bottom of the box, the jaws 79 come to a rest position, but the slide 61 continues its downward movement against the action of the springs 78, and the wedge 81 forces the jaws 79 apart laterally, thus pinching the collar and the body of the box, with the inwardly-turned end of the strip therebetween; between the jaws and dies at the completion of the downward movement of the slide. Simultaneously with the action of the wedge or immediately thereafter a slight additional inward movement is given to both of the movable dies to increase the pinch upon the walls of the box and collar, and thus insure the proper adhesion of all of the parts. The dies are now withdrawn sufficiently to relieve the pressure upon the sides of the box, after which the slide moves upwardly, relieving the wedge action upon the jaws, which are returned to their former position by the springs 82, and relieving the pinching pressure upon the collar and box. The slide continues its upward movement, and as the jaws are withdrawn from the collar the overhanging edges of the folders, by their engagement with the top edges of the box-body, strip the same from the plunger. The two movable dies are now moved outwardly, the movable platform is withdrawn, and the completed box, as shown in Fig. 10, drops downwardly through the bed of the machine into a receptacle conveniently located to receive it.

There are many minor changes and alterations that can be made within my invention aside from those herein suggested, and I would therefore have it understood that I do not limit myself to the exact construction herein shown and described, but claim all that falls fairly within the spirit and scope of my invention.

Having described my invention, what I claim as new, and desire to secure by Letters Patent, is—

1. In a box-machine, the combination with means for centering the box-body; of means for folding inwardly that portion of the paper strip surrounding the same that projects above the top of said box-body; means for inserting a collar within said box-body and turning the inwardly-projecting portion of said strip downwardly, substantially as described.

2. In a box-machine, the combination with dies for centering the box-body; means for moving one or more of said dies; folders yieldingly secured to said dies and arranged so as to turn inwardly that portion of the paper strip projecting above the top of said box-body during the movement of said dies; a reciprocating plunger adapted to carry a collar thereon; and means for actuating said plunger, whereby said collar will be inserted within said box.

3. In a box-machine, the combination with dies for centering the box-body; of folders arranged so as to turn that portion of the paper strip projecting above the top of the box inwardly during the movement of the dies in one direction and to strip the same from the plunger when the plunger is being removed therefrom; a plunger adapted to carry a collar thereon; means for actuating said plunger, whereby the said collar will be inserted within said box and said inwardly-projecting portion of said strip turned downwardly between the outside of said collar and the inside of said box at one and the same time, substantially as described.

4. In a box-machine, the combination with dies; of folders yieldingly connected therewith; means for actuating one or more of said dies; a plunger adapted to hold a collar thereon; means for actuating said plunger, whereby said collar will be inserted within said box; and means for actuating said dies after said collar and plunger have been inserted therein, whereby the sides of said box and said collar will be pinched between said plunger and said dies.

5. In a box-machine, the combination with dies corresponding in number to the number of sides to the box and arranged so as to center said box; of a reciprocating plunger adapted to carry a collar thereon; means for actuating said dies and plunger, whereby said collar is inserted within said box.

6. In a box-machine, the combination with dies; of folders connected therewith; stop means for limiting the movement of said folders in one direction; spring means for moving said folders independently of said dies; and a reciprocating plunger.

7. In a box-machine, the combination with dies; of means for reciprocating one of said dies; folders connected with said dies; a plunger; means for moving said plunger between the inner ends of said folders; and means for holding said folders in their innermost position while said plunger is being withdrawn from between said folders.

8. In a box-machine, the combination with a plunger; of means for reciprocating the same; sliding jaws movably mounted within said plunger; and means operative between said jaws for separating the same.

9. In a box-machine; a plunger; means for reciprocating the same; jaws slidably mounted within said plunger; and a wedge lying between said jaws and adapted during its movement in one direction to force said jaws apart.

10. In a box-machine; a plunger, said plunger comprising a shank member, a head slidably mounted thereon, jaws movably mounted in said head member, and a wedge connected with said shank and lying between said jaws, designed during its movement to open said jaws.

11. In a box-machine; a plunger, comprising a shank member 70, head member 69, jaws 79 movably mounted therein, wedge 81 connected with said shank, a spring-plate 76 connected with said shank, and springs 78 lying between said plate and said head for moving said head in one direction.

In testimony whereof I affix my signature in presence of two witnesses.

HENRY F. ODENKIRCHEN.
